SUCTION CLEANER

Vernon E. Carlson, Canton, Ohio, assignor to The
Hoover Company, North Canton, Ohio, a cor-
poration of Ohio

Application October 21, 1933, Serial No. 694,562

4 Claims. (Cl. 15—179)

The present invention relates to suction cleaners in general and particularly to new and novel improvements in rotary agitators for suction cleaners. More specifically the invention comprises the provision, in a suction cleaner rotary agitator, of a reversible brush construction which makes possible the seating of the brush at a plurality of heights relative to the normal surface of the agitator.

Present day suction cleaner rotary agitator design requires that the agitator be provided with both rigid beating and flexible brushing elements. The life of the bristles of the brushing element is dependent upon the quality of the bristles and also upon the type of service in which the cleaner is used. The rigid beating element of the agitator has an indefinite life which may be said to be that of the cleaner itself. In the well designed rotary agitator the rigid beating element and the flexible brushing element extend to substantially the same height above the normal surface of the agitator body. Stated differently, they extend to substantially the same radial distance from the axis of rotation. In use the brush bristles wear away resulting in a decrease in their radial projection, a condition which if not remedied causes the brushes to cease to be a factor in the cleaning operation. The brush element used in the modern suction cleaner is a replaceable unit of relatively small cost and it has been the practice to remove and replace it when worn and ineffective. Certain agitators have been designed which provide complicated mechanisms to adjust the effective brush bristle length, but because of the relatively small cost of the brushes this has not been commercially feasible.

In the agitator constructed in accordance with the present invention the brush element itself and its seat in the agitator body are so formed and designed as to cooperate to give an effective bristle height which can be changed by a simple adjustment of the brush relative to its seat.

It is an object of the present invention to provide a new and improved suction cleaner rotary agitator. A further object is to provide a new and improved rotary agitator with removable brushes. Still another object is the provision of a rotary agitator with a reversible brush element for a suction cleaner. A still further object is the provision, in a suction cleaner, of a rotary agitator which comprises a brush which is adapted to be placed in a plurality of positions relative to the agitator body for the purpose of

effecting an adjustment of the bristle height above that body. These and other more specific objects will appear upon reading the following specification and claims and upon considering in connection therewith the attached drawings to which they relate.

Referring now to the drawings, in which a preferred embodiment of the present invention is disclosed:

Figure 1 is a side view of a suction cleaner embodying the present invention with a casing of the cleaner partially broken away and showing the agitator positioned within the cleaner nozzle;

Figure 2 is a side elevation of an agitator constructed in accordance with the present invention with certain parts broken away;

Figure 3 is a partial cross section through the agitator showing the brush positioned in its second or reversed position;

Figure 4 is a cross section upon the line 4—4 of Figure 2;

Figure 5 is a section upon the line 5—5 of Figure 3;

Figure 6 is a section upon the line 6—6 of Figure 3;

Figure 7 is a section upon the line 7—7 of Figure 3;

Figure 8 is a view in perspective of a brush element constructed in accordance with the present invention removed from its seat in the agitator body;

Figure 9 is a top view of the brush element. In the drawings, and in Figure 1 in particular, an agitator constructed in accordance with the present invention is shown embodied in a modern suction cleaner. The agitator is indicated generally by the reference character 1 and is shown positioned within the nozzle 2 of the cleaner. A suction-creating fan 3 within the fan chamber 4 is driven by an unshown motor within the motor casing 5 and functions to draw cleaning air between the surface-contacting nozzle lips 6 and 7, into the nozzle 2, through the air passageway 8, and exhausts same from the fan chamber 4 into the exhaust outlet 9 to which is removably attached an ordinary dust bag 10. The cleaner is removably supported by front and rear wheels 11 and 12 and, as in the usual suction cleaner, a pivoted handle 13 is provided by which an operator may exert a propelling force.

The agitator 1, the construction of which comprises the present invention, is formed of an elongated cylindrical body 15 which is rotatably supported at each of its ends upon the stationary through supporting shaft 16 by means of a bear-

ing 17. A stationary thread guard member 18 is carried by the threaded end of the shaft and overlies the end of the cylindrical body 15 to prevent the accumulation of hair and foreign matter about the supporting bearing. A surface of reduced diameter forms a pulley 19 substantially centrally of the agitator body and seats a driving belt 20 which extends rearwardly through the passageway 8 to the driving pulley 21 carried at the lower end of the motor shaft below the suction-creating fan 3. The usual type of rigid beating element 22 extends helically upon the surface of the body 15 from end to end thereof, excepting of course the pulley surface 19. Upon the opposite side of the pulley 19 and extending longitudinally of the body are re-entrant seat portions or channels 25, 25, which are constructed in a definite manner and are adapted to receive and seat removable brushes 26, 26, each of which includes an elongated rigid back 27 which carries tufts of flexible bristles 28, 28 etc.

The opposite ends of the channels 25, 25 are provided with openings, as is clearly seen in Figures 2 to 6, inclusive. At one end, the outer, as seen in Figures 4 and 5, the top of the open end of the brush channel is defined by spaced shoulders 30, 30 between which is formed an upwardly extending recess the top of which is defined by the shoulder 31. The opposite or inner end of the channel 25 is also open at its top being defined by a single shoulder 32, as is clearly seen in Figure 6. As is evident from comparing Figures 4, 5 and 6, the shoulder 32 is at a height in the brush channel 25 midway between shoulders 30, 30 and shoulder 31.

A removable brush 26 is adapted to be received in the channel 25 with its ends extended into the openings thereof, and is also adapted to be removed therefrom and reversed end for end. The insertion and removal of the brush is accomplished by moving the brush in the direction of the pulley and further into the opening in that end of the channel, thereby permitting the opposite end of the brush back to disengage from its opening and move upwardly. The insertion of the brush is exactly the reverse operation. In order to accomplish a brush-height adjusting function upon the brush being reversed end for end the ends of the rigid back 27 of the brush are also shaped in a definite manner, so that they cooperate with the ends of the channel 25. As is seen in Figures 8 and 9, one end of the rigid back 27 is formed with a transverse shoulder 35 which extends the entire width of the back. The opposite end of the back 27 is provided with a central shoulder 36 which extends only partly there across and is at a greater height thereon than is the shoulder 35. The difference between the heights of the shoulders 35 and 36 on the back is exactly that which exists between the shoulders 31 and 32 at the opposite ends of the channel 25. With the brush inserted within the channel in either of its two positions it is contacted along its bottom by a resilient spring 40 which urges it radially outward or upward and the end shoulders thereof into contact with the shoulders defining the tops of the end openings of the channel.

Referring now to Figure 2 of the drawings in particular, the removable brush 26 is shown positioned in the agitator body in its lower or new brush position. In that position the upper shoulder 36 of the brush back underlies the pulley end or inner shoulder 32 in the channel. Lower shoulder 35 at the opposite end of the back underlies the spaced shoulders 30, 30. In Figure 3

the brush has been reversed end for end and the lower shoulder 35 on the back underlies the inner shoulder 32 of the channel while the upper shoulder 36 of the back has been positioned within the recess at the outer end of the channel and contacts the upper shoulder 31 at that end. Brush shoulder 36 has been moved radially outward in the brush body by a distance equal to the difference in height between inner channel shoulder 32 and outer channel shoulder 31. Brush shoulder 35 at the opposite end of the brush has been moved radially outward an equal distance as the difference in height between shoulders 30, 30 and shoulder 32 is equal to the difference existing between shoulders 32 and 31. The brush is seated parallel to the agitator axis in all positions as the difference in height of supporting channel shoulders is equal to the difference in height of the shoulders on the brush back.

When the machine is originally sold the brushes are positioned within the agitator in the position shown in Figure 2. After usage of the machine has worn the bristles so that the brush no longer performs its function it is an easy matter to remove the brush from the agitator, reverse it end for end and to insert in its second position, that shown in Figure 3, and again obtain the desired bristle projection.

I claim:

1. In a suction cleaner, a body having a brush seat, a shoulder extended across one end of said seat, a pair of vertically and transversely spaced shoulders at the opposite end of said seat, a brush comprising a back adapted to be positioned in a plurality of positions in said seat, a shoulder extended across one end of said back, a shoulder at a different height extended partially across the opposite end of said back and arranged to underlie the upper of said spaced shoulders only in one brush position, said shoulders on said back being adapted to selectively co-operate with said shoulders in said seat to position said brush, the construction being characterized by the fact that upon reversal end for end of said brush in said seat said brush assumes a different height in said seat.

2. In a suction cleaner agitator, a body having a brush seat below its surface, said seat having openings at its ends adapted to receive the ends of a brush back, one of said openings having its upper limit defined by a single shoulder, the other opening having its upper limit defined by a plurality of shoulders two of which are vertically and transversely spaced, a brush including a back adapted to be positioned in said seat and having ends adapted to selectively contact said shoulders, one end of said back having a shoulder adapted to contact the lower shoulder at that end of said seat having a plurality of shoulders, the opposite end of said back having a shoulder adapted to slide past said lower shoulder and contact a higher shoulder, said brush being positioned at different heights in its two positions.

3. In a suction cleaner, a body having a brush seat, a brush including a back and bristles positioned in said seat, back-seating means at one end of said seat, contacting means on said back seating on said seating means, cooperating seating and contacting means at the opposite end of said seat and back extended only partially across said seat, second back-seating means spaced vertically and laterally from said cooperating seating means, the vertical distance between said back-seating means at said opposite end of said

5 seat being twice the vertical distance between either of said means and the back-seating means at the opposite end of said seat, said back being reversible in said seat, the contacting means on said back seating on said second back-seating means in the reversed position.

10 4. In a suction cleaner, a body having a brush seat, a shoulder defining the top of an opening at one end of said seat, spaced shoulders defining a part of the top of an opening at the opposite end of said seat, a third shoulder higher in said seat than said spaced shoulders and positioned

therebetween and cooperating therewith to define said opening, a brush in said seat having a rigid back extended the length of said seat and into said openings, a relatively wide shoulder at one end of said back adapted to underlie and contact said spaced shoulders in one position of said brush in said seat, and a relatively narrow shoulder at the opposite end of said back adapted to extend between said spaced shoulders and contact said third shoulder in the reversed position 10 of said brush in said seat.

VERNON E. CARLSON.
